UNITED STATES PATENT OFFICE.

CHARLES A. KLOMAN, OF BELLEVUE, PENNSYLVANIA.

DEVICE FOR CRUSHING COAL AND OTHER MATERIALS.

1,408,607.

Specification of Letters Patent.

Patented Mar. 7, 1922.

Application filed June 25, 1919. Serial No. 306,612.

To all whom it may concern:

Be it known that I, CHARLES A. KLOMAN, a citizen of the United States, residing at Bellevue, in the county of Allegheny and 5 State of Pennsylvania, have invented a new and useful Improvement in Devices for Crushing Coal and other Materials, of which improvement the following is a specification.

My invention relates to improvements in 10 devices for crushing coal and other materials. The objects of the invention are primarily to produce a combined crusher and pulverizer of the simplest construction and the greatest possible efficiency, and secondly, 15 to produce a pulverizer in which friction between the pulverizing surfaces is entirely avoided, and thirdly, to produce a pulverizer peculiarly applicable to the pulverization of coal owing to the avoidance of friction 20 between the pulverizing surfaces. I accomplish these objects by means of the device hereinafter more specifically described reference being had to the accompanying drawings forming a part hereof, in which—

25 Figure 1 is a side elevation of my improved device.

Figure 2 is an end elevation of the same.

Figure 3 is an enlarged end view partly in section of the crusher.

30 Figure 4 is a side elevation of the same partly in section.

Referring to said drawings, 1 is a foundation whereon is erected the frame 2 on the top members 3 of which the hopper 4 and 35 crusher 5 are supported. The said hopper is located beneath the conveyor 6 whereby material to be crushed may be readily conveyed thereto. The said crusher includes a casing in the sides of which the stems or 40 shafts 8, 9 of the downwardly projecting pairs of crusher arms 10, 11 are journalled, an apron 12 which is intended to prevent the crushed or broken material from fouling the bearings of said arms extends around 45 the sides on the interior of said casing, and 13 is a grid which constitutes the bottom of the crusher and forms with said arms a grate for feeding a quantity of crushed material to a chute 14, dependent upon the 50 speed at which the device is operated. Each pair of downwardly projecting crusher arms 10, 11 is geared together by means of the segmental gears 15, 15, 16 and is driven from the shaft 18, mounted in bearings 19, 20 55 formed in the standards 21, 22 secured upon

the members 3; 23 is a gear mounted on said shaft 18 which meshes with and is driven by the worm shaft 24, on the outer end of which the sprocket gear 25 is mounted. The sprocket 23 is driven by a chain or other suitable means from the gear 26 mounted on the power shaft 27 of the motor 28; a cam 29, 30 is mounted on each end of said shaft 18 to which is connected the rods or shafts 31; the outer ends of which are provided with elongated 60 openings or slots 32, in which the blocks 33 are mounted, the pin of the cranks 34 being mounted in said blocks; the segmental gear 15, mounted on each of said cranks which is in fact a continuation of the stem of one 65 of the crusher arms, meshes with, and when said cranks are oscillated transmits power to a corresponding segmental gear 16 mounted on the outer end of the stem of the remaining crusher arm of each pair; the cams 70 75 are arranged on different angularity, there being a difference of 180 degrees between the same so that one pair of crusher arms is oscillated in an opposite direction to that of the other pair of crusher arms; buffer 80 springs 35 are mounted in said slots 32, on each side of the blocks 33 for the purpose of taking up any excessive strain brought to bear upon the crusher arms, as for instance, should a piece of metal, or other extremely hard material 85 be dropped between either one of the pairs the strain would be taken up by the said springs and thus prevent the probable fracture of the arm.

The oscillation of the arms gradually 90 breaks the material fed therebetween until the smallest portion of said material is forced in between the sharp edges of the grids and the lower edges of the crusher-arms which action reduces the material to 95 a comparatively fine or comminuted condition and if it is desirable to reduce the material to a finer condition it may be fed through the chute into a pulverizer 36.

Having described my invention, what I 100 claim and desire to secure by Letters Patent, is:

1. In a device of the kind described, the combination of a crusher comprising a casing having means to feed material thereto, 105 a grid forming the bottom of said casing, a plurality of crushing members adapted to be moved laterally from and towards each other, and an apron located within the casing and extending below and adapted to 110

cover the bearings of said crusher elements, to prevent fouling thereof by the material contained in the casing.

2. In a device of the kind described the combination of a crusher comprising a casing, a grid forming the bottom of said casing, a plurality of crushing members arranged in pairs, the members of each pair being adapted to be moved laterally from 10 and towards each other in close relation to the grid, the pairs of said members being adapted to be alternately moved in opposite

directions from each other, and an apron located within the casing extending below the bearings of said crusher elements so as 15 to protect the same from the material within the casing.

In testimony whereof, I have hereunto signed my name in the presence of two subscribing witnesses.

CHARLES A. KLOMAN.

In the presence of—

JOHN H. RONEY,

CLARENCE A. WILLIAMS.
